SCREENING MECHANISM

Robert P. Miller, San Gabriel, and Frank Mathewson and Gotthold Harry Meinzer, Glendale, Calif.; said Miller and said Mathewson assignors to said Meinzer

Original application September 10, 1949, Serial No. 114,966. Divided and this application January 25, 1952, Serial No. 268,311.

3 Claims. (Cl. 209—332)

This application is a division of our copending application Serial No. 114,966, filed September 10, 1949, and entitled "Screening Mechanism."

This invention relates to apparatus for separating granular and pulverulent solid materials into desired size ranges by passage over and through foraminous media such as wire mesh screens, plastic screen cloth and the like.

The invention is illustrated herein as embodied in a screening apparatus of the type described in United States Patent 2,284,671 entitled "Shaking Device," issued June 2, 1942, to G. H. Meinzer, in which the screening element is subjected to a gyratory motion in a substantially horizontal plane and simultaneously to progress tilting around its own center, reference being made to the said patent for a full description of the basic elements of the structure and the manner in which the described gyratory and tilting movements are produced.

Broadly described, the combination to which the present invention pertains includes a cylindrical frame spanned by a screen, this cylindrical frame with its screen being mounted in a floating manner by suitable support springs on a lower sub-frame. The floating structure, i. e., the upper cylindrical frame, carries on its under side a suitable motor, the motor shaft being upright and carrying an upper unbalanced weight above the motor and a lower unbalanced weight below the motor. It is oscillation of these two eccentric weights that produces the desired gyratory and tilting movements of the floating structure.

Since both the eccentric weights and the motor are suspended from the floating upper cylindrical frame and since these components far outweigh the rest of the floating structure, it is difficult to keep the center of gravity of the floating structure from being too low. If the center of gravity is elevated to the plane of the upper eccentric weight, the oscillatory movement of the floating structure will pivot about the center of gravity in that plane in a highly desirable manner. Moreover the closer the pivot center of oscillation to the screen across the upper cylindrical frame, the less the vibratory stress imposed on the screen.

It is an object of the present invention to elevate the center of gravity of the floating structure including the motor and weights and to minimize the vertical distance of the center of gravity from the screen carried by the upper cylindrical frame. A further object is to provide an efficient bottom structure for the upper cylindrical frame to carry the weight of the suspended motor and eccentric weights.

In general these objects are attained by providing the upper cylindrical frame with a re-entrant bottom wall to provide a space for the upper eccentric weights that is at a relatively high level. Rigidity in the mounting of the motor on the underside of the upper cylindrical frame is important because any flexure on the part of the structure between the eccentric weights and the screen carried by the upper cylindrical frame will not only introduce distortion of the generated pattern of motion, but will also result in fatigue of the support structure. It is apparent that rigidity is paramount and that the rigidity of the bottom structure may be enhanced by a re-entrant configuration for the bottom wall of the cylindrical frame. A conical configuration is preferred.

The advantages of the invention will become evident on inspection of the attached drawings and the following description thereof, in which

2

Fig. 1 is a vertical section on the center line of the assembled apparatus, showing the motor and counterweights in elevation and omitting the clamping ring shown in Fig. 4;

Fig. 2 is a cross section through the subframe A, as on the line 2—2 of Fig. 1;

Fig. 3 is a cross section through the screen-supporting section B, showing certain underlying members in plan, as on the line 3—3 of Fig. 1;

Fig. 4 is a sectional detail through the outer edge of the screen cloth and the rings between which the cloth is retained, showing also the manner of assembling superposed screen frames.

Referring first to Figs. 1 to 3 inclusive, the lowermost element or subframe A of the machine consists of a cylinder 10 of steel plate provided with angle iron flanges 11 and 12 at its lower and upper ends. The lower flange should have several bolt holes 13 for attachment of the subframe to a floor or foundation. As almost no vibration is transmitted to the subframe when the machine is in operation and there is little or no tendency to walk, the foundation of whatever kind need only be sufficient to carry the dead weight of the machine and its operating load.

The upper flange carries a plurality of open coil springs 14, preferably four in number, interposed between the subframe and the screen-carrying frame B. These springs support the screens, motor and other moving parts of the apparatus and permit the screens to gyrate and tilt in the manner described in the Meinzer patent. Generally speaking, the stiffness of the springs should be such that they will be only slightly deflected, in a closing direction, by the dead weight of the supported parts of the mechanism when empty, and only partially closed by the dead weight of these parts when loaded. The lower ends of these springs are rigidly affixed to the upper flange as by bolts 15.

The supporting section B consists of a short steel plate cylinder 16 within which is welded a truncated, relatively flat, steel plate cone 17 which in turn carries a motor housing 18. Radial plates 19 stiffen this structure and prevent vibration of the housing with respect to the cone. A vertical electric motor 20 is supported within the housing on internally projecting rings 21 and 22, the motor being locked in position as, for example, by means of conical wedges 23 and drawbolts 24. Electrical connections may be made to the motor in any convenient manner, as for example through a freely flexible conduit 25 passing through bushings 26 and 27 in the walls of the subframe and housing. The upper ends of springs 14 are bolted to stirrups 28 projected from the lower face of cone 17. A shield plate 29, slightly dished upwardly, is removably bolted over the upper end of the motor housing, and a tension bolt 30 is projected upwardly from the center of the plate. The upper end of cylinder 15 is provided with a flange 31 to which the stack of screen frames is attached as will be described.

The motor 20 is provided, as in the Meinzer patent, with unbalanced weights 32 and 33, attached respectively to the upper and lower ends of the motor shaft 33' in such manner that their radial angle may be varied. Either or both of these weights may also be varied in magnitude, the upper most conveniently by substituting one weight for another, the lower by attachment or removal of bolted-on weights 34.

The stack resting on the upper flange 31 of the supporting section may consist of any required number of screens, reserving that it is undesirable to make the stack so high as to be top heavy. If but two fractions are to be made (one over and one through) only one screen frame will be required, this being the upper frame D. If a greater number of separations are to be made, one or more intermediate frames C must be provided.

The form indicated at D, which in any case will be the uppermost of the stack, is a short cylinder of steel plate having an upper flange 31' and a lower end flange 35. The form indicated at C, which will be used in any intermediate position, has an upper end flange 31'', a lower flange 35', together with a feed return pan 36 and means later described for protecting the periphery of the screen cloth against damage.

The feed return pan, the purpose of which is to collect the undersize passing through the screen next above and direct it to the center of the screen next below, is a shallow cone of light sheet metal having a central opening 37. Over this opening is placed a spider 38 having a central boss 39 from which a tension bolt 30 is directed upwardly.

The screen cloth 40 is mounted in a circular frame composed of two flat metallic rings 41 and 42 (see Fig. 4) and narrow rings 43 and 44 of rubber or other elastic material interposed between the screen cloth and the inner edges of the metallic rings. Before mounting, the cloth is stretched evenly in both directions, in any convenient manner, until it lies flat and smooth, after which the above described rings are applied on opposite sides, the outer edges of the metallic rings are brought into close contact with the cloth, and these edges are spot welded to the cloth and to each other as at 41', after which projecting portions of the cloth are trimmed away, leaving a circle of screen cloth enclosed in a stiff metallic ring in which it is held under such tension as was imparted in the original stretch. The advance preparation of the screen cloth element as above described greatly facilitates the changing of screens and the assembling of a screen stack.

At the center of the screen cloth a hole is punched of such size as to pass over tension bolt 30 so that a suitable nut may be threaded onto the bolt to pull the screen taut in a downward direction. Surrounding this opening and on opposite sides of the screen are placed suitable metal washers to receive the bolt as shown in Fig. 1. The inner edges of the metallic washers are welded or brazed to the screen and to each other.

In the operation of a screen having the combined gyratory and tilting motion described in the Meinzer patent, the forces which produce movement of the feed over the surface of the cloth act tangentially with the result that a particle which remains on the upper surface of the cloth moves in a constantly widening spiral until it encounters the enclosing wall, around which it travels until it escapes through a delivery spout 61 communicating with an opening through the wall. This tendency to travel toward the edge of the cloth is resisted by directing the cone of the screen cloth downwardly, the feed being thus forced to travel uphill to escape. A highly useful control of time of retention of the oversize on any given screen, under fixed conditions of rapidity and magnitude of gyration, may be exercised by varying the slope of the screen cone, an increase in slope increasing retention. This control may be utilized to increase the throughput capacity of the screen or to improve the sharpness of separation between oversize and undersize.

Because the feed travels outwardly over the screen, maximum utilization of the surface depends on feeding each screen centrally. The uppermost screen of the stack is fed in this location through any feed spout (not shown) while the return of the undersize from one screen to the center of the screen next below is effected by conical pans 36, the slope of which must be sufficient to cause gravitation to overcome the tendency of gyration to cause the solids to move outwardly.

As can be understood by reference to Fig. 1, the upper screen of which is assumed to be fed centrally, the over-

size from screen 40 passes out through delivery spout 61, the undersize falling onto pan 36 and passing by gravity to central opening 37 and through it onto screen 40' of the next finer mesh. The oversize from screen 40' passes out through spout 61' and, as this is the last screen in the stack illustrated, the undersize falls onto shield 29 and cone 17 and passes out through spout 61".

We claim as our invention:

1. In screening mechanism of the type in which rotation in substantially horizontal planes of a pair of spaced, unbalanced weights imparts motion to a horizontally disposed screening member; an upright subframe; a cylindrical frame above said subframe; a partition member extending across said cylindrical frame and united therewith, said partition being in the form of a cone with its apex uppermost and with its lower periphery positioned generally horizontally; a plurality of open coil springs in compression between said partition member and said subframe for resilient support of the partition member together with the cylindrical frame; a motor spaced below said partition member, said motor being rigidly connected to the underside thereof; a shaft extending upward from said motor towards said partition member; unbalanced weights on said shaft inside the conical configuration of said partition member above the plane of the periphery of the partition member; and a screen cloth extending across said cylindrical frame above said partition member, there being an opening adjacent the periphery of said screen cloth for the continuous discharge of material too large for the mesh of the screen cloth and opening near the periphery of said partition member for the continuous discharge of material that passes through said screen cloth.
2. A screening mechanism as set forth in claim 1 which includes means extending upward from said partition member to draw the central portion of said screen cloth downward to form the screen cloth into a shallow cone.
3. In screening mechanism of the type in which substantially horizontal rotation of unbalanced weight imparts motion to a substantially horizontally disposed screen; a subframe; a screen-carrying frame; coil springs resiliently supporting the screen-carrying frame above the subframe; a partition connected to and extending across the screen-carrying frame; a motor rigidly supported by the screen-carrying frame below the partition; a shaft extending upwardly from the motor; an unbalanced weight on said shaft, said partition being upwardly inclined toward its center to provide space for said weight; and a screen connected to and extending across the screen-carrying frame above the partition, said screen-carrying frame having an opening for discharge of oversize from the screen cloth and an opening for discharge of undersize which passes through the screen cloth onto the partition.
